UNITED STATES PATENT OFFICE.

ALONZO C. SCHATZ, OF WHEATON, ILLINOIS.

IRONING-BOARD.

SPECIFICATION forming part of Letters Patent No. 728,306, dated May 19, 1903.

Application filed January 19, 1903. Serial No. 139,532. (No model.)

To all whom it may concern:

Be it known that I, ALONZO C. SCHATZ, a citizen of the United States, residing at Wheaton, in the county of DuPage and State of Illinois, have invented certain new and useful Improvements in Ironing-Boards, of which the following is a full, clear, and exact specification.

My invention relates more particularly to ironing-boards for ironing puff sleeves, and has for its primary object to provide an improved and peculiar form of two-part ironing-board especially adapted for ironing the gathering in the puff of the sleeve and capable of being readily inserted thereinto.

With these ends in view my invention consists in certain features of novelty in the construction, combination, and arrangement of parts by which the said object and certain other objects hereinafter appearing are attained, all as fully described with reference to the accompanying drawings and more particularly pointed out in the claim.

In the said drawings, Figure 1 is a side elevation of my improved ironing-board. Fig. 2 is a plan view thereof. Fig. 3 is an end view; and Fig. 4 is a detail plan view of the end of the board, showing the head detached and also illustrating a modification in the form of the head.

In carrying my invention into effect I prefer to support the ironing-board proper upon a portable stand, which may be in turn supported upon a table, a chair, or any other suitable support and suitably clamped thereto or not, as desired. This stand preferably consists of a base 1, which may be of any convenient or suitable length or width, and a pair of standards 2 3, secured thereto and rising therefrom at points near the ends of the base and in a line passing substantially through the center thereof. These standards 2 3 are shown as braced by corner-brackets 4 5.

The standard 3 in its inner side and near its upper end is provided with a socket 6, which receives one end of the ironing-board proper, 7, and supports the same, while the other standard 2 is provided on its upper end with a pin or post 8, which enters a perforation or socket 9 in the board 7, and thus holds the

board against longitudinal movement, while the socket 6 holds one end against vertical movement. The board 7 is in the form of a narrow strip adapted to be inserted through an ordinary sleeve, and its main function is the support of a head 10, which is detachably secured to one end of the board 7, where it projects considerably beyond the standard 2. As a convenient and efficient means for effecting this detachable connection between the head 10 and board 7 I have shown the projecting end of the board 7 provided with a pair of dowels 11, which enter corresponding sockets 12 in the head 10. The head 10 is of peculiar formation. Its outer edge or end is rounded from side to side, as shown in Fig. 2, and it projects laterally a considerable distance in both directions beyond the board 7. These lateral projections have beveled or tapering shoulders 10^a extending inwardly to a narrow neck portion 10^b, in which the sockets 12 are formed, and which neck portion constitutes a continuation of the board 7, it being of substantially the same width. In the form shown in Fig. 2 the outer ends of the said lateral projections are squared off, so as to form two points 10^c 10^d on each.

13 is a reinforcing-strap secured over the upper end of standard 3 for reinforcing the socket 6 therein.

In the use of the device the head 10 is first detached from the board 7, which, in effect, constitutes a stock or support for the head. The board is then inserted through the sleeve 85 with the dowels 11 contiguous to the puff, the opposite end of the board, which is shown in dotted lines in Fig. 2 as slightly rounded, being inserted foremost. The head 10 is then introduced in the puff of the sleeve through the body portion of the garment and secured on the dowels 11. The board, with the head attached, is then replaced on the standards 2 3, as shown in Figs. 1 and 2, holding the puff elevated on the head 10 and at the outer side of the standard 2 with the curved seam which connects the sleeve and the armhole substantially parallel with the curved outer end or edge of the head 10. By a proper adjustment and manipulation of the puff on the head, bringing the corners 10^c 10^d into the creases produced by the gathering, the

puff may be readily ironed without creasing it, the bevel or inclined shoulders 10^a being utilized for fitting those folds of the puff produced by the gathering in the lower part of 5 the puff or part which joins the puff to the sleeve proper.

In the form of head illustrated in Fig. 4 the shoulders 10^c are dispensed with, and the outer curved edge of the head is carried inwardly until it adjoins the shoulder 10^a. This form of head is better adapted for ironing puffs of children's sleeves or very small puffs in which the folds produced by the gathering are too acute in their angularity to admit of 10 the more obtuse shoulders 10^c 10^d characteristic of the head shown in Fig. 2.

A further advantage in making the heads detachable from their stocks or boards 7 is

that the same stock or board may be utilized for supporting the different heads.

Having thus described my invention, what I claim as new, and desire to secure by Letters Patent, is—

In an ironing-board for ironing the puffs of sleeves the combination of a narrow stock or board, standards for supporting said stock or board and beyond one of which said stock or board projects horizontally and a head carried by said horizontal projection and having lateral tapering extensions and a rounded 25 outer end, substantially as set forth.

ALONZO C. SCHATZ.
